Primary Examiner — Jack Reickel*Assistant Examiner* — Salamah Jordan(74) Attorney, Agent, or Firm — Melissa B. Neely(57) CLAIM

The ornamental design for the personal workout vest, as shown and described.

DESCRIPTION

FIG. 1 is a front view of the personal workout vest, showing my new design.

FIG. 2 is a front-right side view of the personal workout vest.

FIG. 3 is a top and back perspective view of the personal workout vest.

FIG. 4 is a back view of the personal workout vest.

FIG. 5 is a front-left side view of the personal workout vest; and,

FIG. 6 is a back-side view of the personal workout vest. The broken lines in the drawings are for the purpose of illustrating environmental features which form no part of the claimed design.

1 Claim, 6 Drawing Sheets(56)
